(57) **CLAIM**

We claim the ornamental design for an electric city scooter, as shown and described.

DESCRIPTION

FIG. 1 is a perspective view of an electric city scooter embodying the invention.

FIG. 2 is a left side elevation view of the electric city scooter shown in FIG. 1.

FIG. 3 is a right side elevation view of the electric city scooter shown in FIG. 1.

FIG. 4 is a front view of the electric city scooter shown in FIG. 1.

FIG. 5 is a rear view of the electric city scooter shown in FIG. 1.

FIG. 6 is a top view of the electric city scooter shown in FIG. 1; and,

FIG. 7 is a bottom view of the electric city scooter shown in FIG. 1.

The broken lines shown in the drawings illustrate portions of the electric city scooter that form no part of the claimed design.
